UNITED STATES PATENT OFFICE.

MOSES O. GEORGIA, OF FACTORYVILLE, PENNSYLVANIA.

COMBINED SPARK-PLUG PRIMER, COMPRESSION-INDICATOR, AND PRESSURE-GAGE.

1,247,816.

Specification of Letters Patent. Patented Nov. 27, 1917.

Application filed July 12, 1916. Serial No. 108,866.

To all whom it may concern:

Be it known that I, MOSES O. GEORGIA, a citizen of the United States, residing at Factoryville, in the county of Wyoming and State of Pennsylvania, have invented certain new and useful Improvements in Combined Spark-Plug Primers, Compression-Indicators, and Pressure-Gages, of which the following is a specification, reference being had to the accompanying drawings.

This invention relates to internal combustion engines and particularly to spark plugs therefor.

One object of this invention is to provide convenient means for determining the degree of compression in the cylinder of an internal combustion engine and thus determining whether there is leakage in the cylinder or valves.

Another object is to provide convenient means for determining whether or not a cylinder is firing.

A still further object is to provide a combined spark plug and indicator for the purposes above described and in this connection to provide a switch whereby the electrode of the spark plug may be short circuited.

Another object is to so form the combined spark plug and indicator that the spark plug may be used for priming the engine.

A still further object is to so construct the compression indicator that a movable member will be shifted along a scale by the compression within the cylinder and left in its shifted position so that it may be easily read.

Other objects will appear in the course of the following description.

My invention is illustrated in the accompanying drawings, in which,

Figure 1 is a vertical section through a combined spark plug and pressure gage constructed in accordance with my invention;

Fig. 2 is an end elevation, the valve 19 being in section on the line 2-2 of Fig. 1;

Fig. 3 is a sectional perspective view, the section being taken on the line 3-3 of Fig. 1; and

Fig. 4 is a fragmentary sectional view through the valve casing 18 and a part of

the electrode 12, the section being taken at 55 right angles to the section in Fig. 1.

Referring to these figures, 10 designates the base or bushing of a spark plug, this base being of metal and being exteriorly screw threaded for engagement with the walls of the cylinder A. The base 10 has the usual form and is adapted to be engaged at its upper end by the screw-threaded gland 11. Disposed within the base and held in place by the nut or gland 11 is the core or sleeve 12 of insulating material such as porcelain, and passing up through this sleeve and extending downward into the hollow base is a tubular electrode designated 13, the upper portion of which is reduced in exterior diameter and projects beyond the insulator 12 and is exteriorly screw threaded for engagement by the packing nut 14 and the binding nut 15. The bore 16 extends entirely through the electrode and is of uniform diameter and the lower end of the electrode is oppositely beveled so as to bring the electrode to a relatively sharp edge. The sharp edge of this electrode coacts with an electrode 17 75 extending from the bushing or base 10.

Having screw threaded engagement with the upper extremity of the electrode 13 is a valve casing 18 having a rotatable valve 19 adjacent its lower end and a rotatable valve 20 adjacent its upper end, each of these valves comprising a stem which has a diametrical passage and a wing whereby the valve may be rotated. On the stem of the valve 19 there is an electrically conductive arm 21 which is adapted to electrically engage with the gland nut 11 when the valve 19 is turned to establish communication through the bore 16.

Extending laterally from the casing 18 and disposed between the valves 19 and 20 is a tubular barrel 22 within which operates a piston 23 or plunger carrying at its outer end a head 24 operating in an enlarged barrel 25 wherein is disposed a coil spring 26 which resists the outward movement of the piston. The extremity of the barrel 25 is closed by means of a removable plug 27. The barrel 25 is longitudinally slotted as at 28 and connected to the piston head 25 is a member 29 which extends out through the slot 28 and projects into contact with a lug 30 on a slide 31. This slide 31 is mounted

on a laterally projecting rib 32 formed in one piece with the barrels 22 and 25 and this rib has upon one face the graduated scale 33 with which this slide coacts. Operatively mounted to engage the slide 31 is a spring 34 which acts to permit the outward movement of the slide but restrains its inward movement. Now when the piston 23 moves outward under the impulse of compression within the cylinder of the engine for instance, the finger 29 engages the lug 30 and the slide moves outward against the force of the spring 26. When, however, this spring 26 forces the piston back, the spring 34 holds the slide from its return movement so that the position of the slide on the graduated scale 33 may be readily seen.

The operation of my invention is as follows: Under ordinary circumstances, both of the valves 19 and 20 are closed, the arm 21 in this case not contacting with the gland nut 11. The electrode 13 is connected to a source of electricity as, for instance, the usual battery by means of conductor 35 in the usual manner. Under these circumstances the spark plug acts as an ordinary spark plug and fulfills all the functions thereof. In order to prime the engine it is only necessary to turn both of the valves 19 and 20 to such position that the passages through the valve stems align with the longitudinal passage through the valve casing 18 and the electrode wherupon fuel may be directed into the cylinder in the usual manner for priming.

In order to find if there is a leakage in the cylinder or the valves, the valve 20 is turned so as to close the upper end of the passage 16 and valve 19 is turned so as to open this passage and, at the same time, short circuit the spark by reason of the engagement of the arm 21 with the gland nut 11. Under these circumstances the barrel 22 is open to the bore 16 and if the indicator does not show full compression or the proper degree of compression when the engine is running, then there is leakage in the cylinder or valves. In order to find out if the cylinder is firing properly, the switch 21 is closed and the degree of compression noted as directed for testing the cylinder for leakage. The valve 19 is then turned just enough to open the switch, that is to carry the arm 21 out of electrical engagement with the gland nut but without, however, closing the passage through the valve stem of the valve 19. If now the indicator does not register a higher pressure than it did when the switch was closed then the cylinder is not firing.

Attention is particularly called to the fact that this pressure gage which I have described registers the pressure for the reason that when the slide moves forward or

outward along the gage 33 it stays at its maximum position so that the indicator may be read afterward. The slide can be moved back to zero by hand after the test is made.

While I have illustrated a construction which I believe to be particularly effective and thoroughly convenient, it is to be understood that I do not wish to limit myself to the exact details shown or to the exact arrangement of parts as it is obvious that many changes might be made in these details and in the arrangement without departing from the spirit of the invention.

What I claim is:

1. A spark plug having a duct extending through it, a pressure indicator mounted on the plug and connected to the duct, and a valve between the inner end of the plug and the pressure indicator to establish or disestablish communication between the duct and the pressure indicator.

2. A spark plug having a duct extending entirely through it and having a pair of valves independently movable to establish or disestablish communication entirely through the duct and a pressure indicator disposed between said valves and operatively connected to the duct.

3. A spark plug having a tubular electrode, a pressure indicator operatively connected to the bore of the electrode and including a visible movable member, and means for establishing or disestablishing communication between the pressure indicator and the bore of the electrode.

4. A spark plug having a duct extending entirely therethrough, a pressure indicator operatively connected to the duct, and valves one on each side of the point of connection of the duct to the pressure indicator whereby the duct may be opened for its entire length or whereby connection may be established or cut off between the duct and the pressure indicator.

5. A spark plug having a duct, an outer and an inner valve controlling passage through the duct, a pressure indicator mounted on the plug and connected to the duct between the valves, and means carried by the inner valve for short circuiting the spark plug when the inner valve is in open position.

6. A spark plug having a tubular electrode and also having a valve casing into which the upper end of the electrode opens, a pair of valves in said valve casing, a plunger chamber opening to the bore of the valve casing between the valves, a scale, and an indicating member operatively connected to the plunger, and operating over said scale.

7. A spark plug including a valve casing and a duct opening into the valve casing, a plunger barrel extending from said valve

chamber above the valve therein, a spring resisting movement of the plunger, a scale, a sliding indicator coacting with the scale, and operative connections between the plunger and said indicator.

8. The combination with a spark plug having a duct, of a pressure indicator comprising a barrel communicating with the duct and having a plunger therein, an enlarged barrel into which the plunger projects, a spring in the enlarged barrel resisting the outward movement of the plunger, said barrel having a rib formed thereon, the face of which is graduated, a slide mounted upon said rib and constituting an indicator and coacting with the graduations, said slide having a lug, a finger carried by the plunger passing through a slot in the enlarged barrel and engaging said lug for movement in one direction, and a spring yieldingly engaging the indicator slide and restraining it from inward movement.
9. A spark plug including a bushing, a tubular electrode, insulation between the bushing and the electrode, a valve casing mounted upon the upper end of the electrode and having a longitudinally extending bore entirely therethrough, a pair of valves mounted in the valve casing and controlling the passage through the bore thereof, the lower of said valves being provided with a conductive arm adapted to operatively and electrically engage the bushing, a plunger barrel extending from the valve casing between valves, a plunger therein, a spring containing barrel in alignment with the first named barrel, a spring therein urging the plunger rearward, a scale, an indicator mounted upon the barrels and movable over said scale, means carried by the plunger for carrying said indicator outward upon an outward movement of the plunger, and means for holding the indicator in its projected position.
- 45 10. A spark plug having a duct, a pressure indicator operatively connected thereto, means for establishing or disestablishing communication between the duct and the pressure indicator, and means for automatically short circuiting the electrode of the spark plug when communication is fully established between the pressure indicator and said duct, said means permitting, however, the breaking of the short circuit while the duct and pressure regulator are still connected.

11. A spark plug including a base, a gland nut coacting therewith, an insulator disposed within the base and held in position by the gland nut, a tubular electrode passing through the insulator, the base being formed with an electrode coacting therewith, binding screws mounted on the upper end of the electrode, a valve casing mounted on the upper end of the electrode and having upper and lower rotatable valves, the lower of said valves being provided with a conductive arm adapted to engage with the gland nut, a barrel connected to the valve casing between the valves thereof, a plunger operating within the barrel, a spring resisting outward movement of the plunger, a scale carried by the barrel, a slide mounted on the barrel and coacting with the scale forming an indicator, and means causing the unitary outward movement of the plunger and the slide.

12. In a spark plug, a tubular electrode, a valve casing detachably connected to the upper end thereof having a pair of valves, and means connected to the valve casing between the valves for indicating pressure in the bore of said electrode.

In testimony whereof I hereunto affix my signature in the presence of two witnesses.

MOSES O. GEORGIA.
